CLAIM

The ornamental design for a toothbrush handle, as shown and described.

DESCRIPTION

FIG. 1 is a right side elevational view of a first embodiment of a toothbrush handle the left side being identical;

FIG. 2 is a front elevational view of the first embodiment according to FIG. 1;

FIG. 3 is a right side elevational view of a second embodiment of the toothbrush, the left side being identical; and, FIG. 4 is a front elevational view of the second embodiment according to FIG. 3.

The top, bottom and rear of the toothbrush handle as well as all structures drawn in phantom line form no part of the claimed design.
